UNITED STATES PATENT OFFICE.

CHARLES ANESHAENSEL, JR., OF INDIANAPOLIS, INDIANA.

WATER-PUMPING APPARATUS.

SPECIFICATION forming part of Letters Patent No. 660,239, dated October 23, 1900.

Application filed March 5, 1900. Serial No. 7,332. (No model.)

To all whom it may concern:

Be it known that I, CHARLES ANESHAENSEL, Jr., a citizen of the United States, residing at Indianapolis, in the county of Marion and State of Indiana, have invented certain new and useful Improvements in Water-Pumping Apparatus, of which the following is a specification.

My present invention is designed for use in that class of apparatus wherein a water-motor is devoted to use in pumping water for household or such like purposes; and it especially consists in a valve apparatus whereby that water which is pumped is enabled to shut off the supply of that water by which the motor is driven from said motor when a predetermined pressure is reached in the pipes containing the water which is pumped.

As is well known to those familiar with the subject, one great difficulty attending the use of water-motors in pumping water for domestic purposes has been that the motor is kept continuously under pressure from the water which drives it, and this occasions incessant wear upon the valves of the motor, which rapidly destroys its efficiency. This trouble is aggravated by the fact that for a considerable portion of the time such a motor is driven slowly back and forth by the small amount of water which passes through it when not in very active operation, at which times, as those familiar with the subject well know, such sand and grit as may be carried by the water remains in the valves more persistently and cuts said valves more seriously than when it is rapidly washed through, as when the motor is in full operation.

It will be understood, of course, that the water for driving the motor is that usually supplied under "city pressure" from the waterworks, while that to be pumped is usually rain-water from a cistern.

Referring to the accompanying drawings, which are made a part hereof, and on which similar reference characters indicate similar parts, Figure 1 is a side elevation illustrating in a diagrammatic manner a household water system embodying my present invention; Fig. 2, a central sectional view of the valve apparatus which constitutes the leading feature of said invention; and Fig. 3, a detail view similar to a portion of Fig. 2,

but with the valve seated or closed instead of open.

In operation the water which operates the motor (hereinafter denominated the "city water," which it usually is) comes from the mains or source of supply through the pipe 1 to the motor 2, and the waste from said motor runs off into the sewer or other place of discharge through the exhaust or waste pipe 3. My improved valve is interposed in the pipe 1 a suitable distance from the motor 2.

The water to be pumped (hereinafter denominated the "cistern-water," which it usually is) is supplied to the pump-motor through the suction-pipe 4 and is delivered from said pump-motor to the plumbing-fixtures or tank, or both, through the pipe 5, which may or may not have branches, as b, running to various points, according to the plumbing system employed. I have shown the main pipe as running through a check-valve 6 to the tank 7, and said tank has a delivery-pipe 8 and a waste or overflow pipe 9, and to the latter in a modern plumbing system I prefer to connect the hot-water safety-pipe 10. All these matters, however, are matters of choice or preference and are arranged according to the taste of the user or the requirements of the situation to which they are to be adapted. From the pipe 5, however, runs a branch pipe 26 to a suitable chamber in the valve structure. Briefly stated, the operation of this device is: When sufficient cistern-water has been pumped to produce the predetermined pressure in the pipe 5 and in the branches or fixtures which it supplies, said pressure will overcome the spring 24 of this valve structure and shut off the city water which is passing through the pipe 1. This will now be described more in detail. Referring now more especially to Fig. 2, the construction and operation of this controlling-valve will be observed. The valve proper is not dis-

similar to valves of ordinary construction and consists of the usual globe-shaped shell 20, containing a suitable valve-seat 21, with a valve 22, operated by a valve-stem 23, which passes up through the valve structure and is operated in one direction by the spring 24, while it is operated in the other direction by the cistern-water pressure coming through the branch 26 from the pipe 5.

against the cup 25, carried by the valve-stem. The pressure on the valve 22 is counteracted by a corresponding pressure on the cup 27, said valve and said cup or any suitable opposing surface being of the same diameter, and thus constituting a balanced valve. The cup or piston 25, however, is of much larger diameter and is contained within a correspondingly-large chamber in the shell 28, which is mounted on the neck of the globe-valve shell 20, as shown. The stuffing-box 29 on top of this chamber, through which the valve-stem 23 passes, is preferably cup-shaped at the upper end to receive a lubricant, as well as the lower end of the spring 24. The lower side of the chamber, below the cup 25, has a small vent *v* communicating with the outer air in order that there shall be no air compression within this chamber under said cup to impede its operation.

Having thus fully described my said invention, what I claim as new, and desire to secure by Letters Patent, is—

1. The combination, in a water-pumping apparatus, with a water-motor pump, and pipes leading to and from the same, of an automatic stop-valve interposed in the pipe supplying the water for driving the motor, a casing extending upward surrounding the stem of said valve, a surface, as 27, above and opposing the top surface of said valve and balancing the same, a cup or piston on said valve-stem in an enlarged portion of said casing, a spring on an extended upper portion of said stem arranged to normally hold said valve open, and a connection leading from above the piston or disk to pipe through which the water is forced from the pump, all substantially as set forth.

2. The combination in a water-pumping apparatus, with the water-motor pump and

the pipes leading thereto and therefrom, of an automatic single-seat stop-valve interposed in the pipe supplying the water for driving the pump, a casing surrounding the 45 stem of said valve and containing an enlarged chamber, a piston in said chamber of a size larger than the valve and located above it, a pipe leading from said chamber above said piston to the pipe through which the water 50 is forced by the pump, and a surface opposed to and balancing the valve mounted on the valve-stem and free from any seat, substantially as set forth.

3. The combination, in a water-pumping 55 apparatus, with the motor-pump, and the pipes leading thereto and therefrom, of an automatic stop-valve interposed in the pipe supplying the water for driving the motor, said valve being mounted in a casing extending upwardly from the top of said pipe, and having a stem which extends through said casing to outside the water-chamber, a spring surrounding the top of said stem arranged to act against the pressure of the water and normally hold said valve open, a disk opposed to and balancing said valve mounted on said stem free from any seat, a piston or cup above said disk in an enlarged portion of said casing, an air-vent below said piston, and a 70 pipe connecting the chamber above said piston with the pipe through which the water is forced by the pump, substantially as set forth.

In witness whereof I have hereunto set my 75 hand and seal, at Indianapolis, Indiana, this 28th day of February, A. D. 1900.

CHARLES ANESHAENSEL, JR. [L. S.]
